(57) **CLAIM**

The ornamental design for a jewelry setting, as shown and described.

DESCRIPTION

FIG. 1 top plan view of a jewelry setting according to my new design;

FIG. 2 is a side elevational view thereof, all sides being identical;

FIG. 3 is a bottom plan view thereof; and,

FIG. 4 is a sectional view taken on line 4-4 of FIG. 1. The dashed lines in the drawings are for environmental purposes and form no part of the claimed design.
